CARD SORTER

George H. Kress, Vestal, N. Y., and Carl W. Sundberg, Detroit, Mich., assignors to International Business Machines Corporation, New York, N. Y., a corporation of New York

Application November 29, 1949, Serial No. 6,313

Term of patent 14 years

(Cl. D64—11)

To all whom it may concern:

Be it known that we, George H. Kress and Carl W. Sundberg, citizens of the United States of America, residing respectively at Vestal, county of Broome, State of New York, and Detroit, county of Wayne, State of Michigan, have invented a new, original, and ornamental Design for a Card Sorter, of which the following is a specification, reference being had to the accompanying drawings, forming part thereof.

Fig. 1 is a perspective view of a card sorter, embodying our design.

Fig. 2 is a front elevation of the same.

Fig. 3 is a side elevation of the same as seen from the left.

Fig. 4 is a side elevation of the same as seen from the right.

The rear side of the card sorter is plain.

We claim:

The ornamental design for a card sorter, as shown and described.

GEORGE H. KRESS.
CARL W. SUNDBERG.
